ERIK MOERCH, OF PARIS, FRANCE

PROJECTION ARRANGEMENT FOR ADVERTISING PURPOSES

Application filed May 20, 1929. Serial No. 364,581.

The present invention relates to a screen projection arrangement for advertising purposes, which is chiefly characterized by the fact that the characters to be projected are

5 formed upon a flat disk of transparent material, such as glass, the said disk being rotated in such manner that the said characters will travel between the illuminant and the projecting lens.

10 In the accompanying drawings and by way of example:

Fig. 1 is a view of the ensemble of the arrangement.

15 Fig. 2 is a vertical section of the apparatus according to the invention.

Fig. 3 is a corresponding cross section.

Fig. 4 is a plan view.

Fig. 5 is a detail of the construction.

20 The letters or other characters, or designs, employed for advertising purposes are formed upon the face of a flat disk 1 of transparent material, according to a circle or a spiral. The said disk 1 has a central hole 2 and another hole 3 formed in the surface of the disk which does not carry the said characters to be projected. The holes 2-3 can be engaged upon the projection 4 on the axis of a rotatable disk 5 adapted to turn the said disk 1, and upon a stud 6 projecting from the upper face of the disk 5. The shaft 7 of said disk 5 is supported by lugs 8-9 pertaining to the main frame 10. Said frame comprises a bearing 11 in which is mounted a shaft 12 carrying at one end a worm 13 and at the other end a worm wheel 14; said worm engages a worm wheel 15 mounted on the shaft 7 of the said disk 5. The worm wheel 14 cooperates with a worm 16 mounted on the shaft 17 of an electric motor 18, which motor and shaft are disposed upon the said main frame 10.

25 To the shaft 17 of the motor 18 is secured a ring 19 upon which are mounted the respective ends of elastic strips 20 carrying the small blocks 21. The other ends of said strips are secured to another ring 22 which is slidable lengthwise on the shaft 17 and has a radial friction surface 23 cooperating 50 with a brake shoe 24 mounted on a lever 25.

Said lever is mounted on the frame 10 and is controlled by a rod 26, screwed into said frame, which can be moved by means of the milled knob 27.

30 The frame 10 carrying the whole mechanism is angularly movable about a vertical axle 28 situated at one of its ends. The shaft 7 of the disk 5 may thus be displaced according to a cylindrical surface. Said frame 10 is provided with a lug 29 to which is attached the end of a spring 30 whose other end is secured to a casing 31 which contains the whole mechanism. The frame 10 may be given various positions, as well as the shaft 7 of the disk 5, by the following means. 35

35 The said disk 5 has formed on its under surface a spiral groove 32 cooperating with the pointed end 33 of a pivoted lever 34 whose horizontal axle 35 is mounted in a forked bracket 36 secured to the casing 31. 40 When the lever 34 is moved, the said pointed end is released, and the contrary movement will engage the said end in the groove 32 of the disk 5. The said lever 34 carries an adjustable stop 35' limiting the extent of its 45 angular motion when the end 33 is engaged in the said groove 32 of the disk 5. In like manner, the casing 31 is provided with an elastic stop 36' limiting the angular motion of the frame 10 when the pointed end 33 is 50 released and the spring 30 moves the whole device. The combination of the lever 34, the spiral groove 32 and the spring 30 permits the radial motion of the disk 5 when it rotates, in order to effect the successive 55 projection of the characters of the transparent disk 1. Inclined planes 34' and fingers 34'' carried by the disk 5 operate, when this disk is in rotation, upon the lever 34 in order 60 to bring again the system in the position of the projection initial, when the last line of 65 the designs is being projected.

70 On the casing 31 is mounted a right angular partition. The vertical portion 37 of said partition separates the chamber containing the described mechanism from the chamber containing the illuminant. The horizontal portion 38 is parallel to the transparent disk 1, and has an aperture 39 in which 75 is mounted a lens 40 preceded by a diaphragm 80

41 limiting the width of the beam from the illuminant 42 before which it is disposed and which is mounted on a removable casing 43 adapted to close the corresponding chamber 5 31; said casing or cover 43 comprises a fixed part which extends above the horizontal part 38 of the partition, and to which the other part 43' of the cover is hinged. This latter part is movable to give access to the mechanism and to allow the rotating disks 1 to be 10 changed. On the fixed part of the said cover and in front of the lens 40 is disposed the metal tube 44, which can be suitably moved, of a screen projection lens. The electric 15 lamp 42 forming the illuminant has upon its wall a silvered part 45 forming a reflector. The lamp and the electric motor rotating the transparent disk 1 are connected to the terminals of the same electric circuit, a rheostat 46 20 being mounted in the motor circuit.

To receive the beam of light which is vertically projected, the said apparatus is combined with a screen consisting of a prismatic box 47 having one side open and comprising 25 a horizontal face 48 of ground glass, perpendicular to the projection beam issuing from the tube 44. Above the ground glass is mounted a mirror 49 in the 45° position upon which is formed the moving image of 30 the characters on the disk 1. The device is completed by two end parts 50 of black metal plate.

I claim:

1. In a luminous projection apparatus for 35 advertising purposes, a flat transparent disk having advertising characters thereon in a spiral formation, a horizontal rotatable carrier disk having the transparent disk removably mounted thereon, means for rotating said disk and controlling the speed of 40 rotation, the carrier disk having a spiral groove formed in its under side, a radial arm mounted at one side of said disk with its free end arranged to engage said groove, a pivotally mounted frame carrying the driving mechanism and said carrier disk, a traction spring connected to the frame and urging 45 the side of the groove against said arm, and means for projecting enlarged images of the 50 characters on said transparent disk.

2. In a luminous projection apparatus for 55 advertising purposes, a flat transparent disk carrying advertising characters, a horizontal rotatable carrier disk adapted to receive and carry said transparent disk, a casing containing 60 the disks and the means by which the same can be rotated and also moved crosswise, a right angular partition in the said casing, an illuminant at the rear of said partition, an aperture in said partition in front of 65 the luminous beam projected by the illuminant, a lens disposed in said aperture, a diaphragm cooperating with said lens, a cover adapted to cover the said casing and disk, 70 and a lens tube mounted on said cover and

cooperating with the lens, the cover having a constricted portion into which the transparent disk marginally projects between the lens and the diaphragm.

3. In a luminous projection apparatus for 70 advertising purposes, a flat transparent disk carrying advertising characters in spiral formation, a rotatable carrier disk adapted to receive the transparent disk, and provided with a spiral groove in its under side, a radial 75 arm which is angularly movable and engages the said groove, a pivoted frame carrying the driving mechanism and the disks, a spring urging said frame and thus pressing the side of the groove against the radial arm, 80 a casing containing the whole mechanism, a partition in said casing having an aperture through one end portion, an illuminant at the rear of said partition in position to project a beam of light through said aperture, a 85 lens disposed in said aperture, a diaphragm cooperating with said lens, and an adjustable lens tube alined with the lens and the opening in the diaphragm, the disk projecting marginally between the lens and the diaphragm 90 to dispose the advertising characters in the beam of light.

4. A luminous projecting apparatus comprising a transparent disk having characters thereon in spiral formation, projecting and illuminating elements arranged to project a beam of light through the characters on the disk, a pivoted frame, a rotatable carrier disk receiving and carrying the transparent disk and having a spiral groove in its under side, 95 means on the frame for supporting and rotating said carrier disk, an arm mounted adjacent the carrier disk and extending over the same with its free end engaging the groove therein, and means on the carrier disk to engage the arm for positioning the disk.
